Term of patent 7 years

(Cl. D54—12)

FIG. 1

FIG. 2

FIG. 3

FIG. 1 is a front view of a fork embodying my design,
FIG. 2 is a side view of said fork,
FIG. 3 is a rear view of said fork,
FIG. 4 is an end view of said fork, and
FIG. 5 is an enlarged sectional view thereof taken on line 5—5 of FIG. 1.

The unillustrated side of said fork is the same as the illustrated side. The mid-section of the handle is stip-pled to indicate a contrast between the surface appearance of the mid-section and end portions of the handle.

I claim:

The ornamental design for a fork or similar article,
substantially as shown and described.
